(57)

CLAIM

The ornamental design for hats, as shown and described.

DESCRIPTION

1. Hat

2. Hat

1.1 : Perspective

1.2 : Top

1.3 : Front

1.4 : Right

1.5 : Bottom

2.1 : Perspective

2.2 : Top

2.3 : Front

2.4 : Right

2.5 : Bottom

The object of this industrial design is a headwear in the form of a harmonious three-dimensional shape of a bowler hat, the upper part of which has the shape of the upper parts of a baseball cap with crowns, consisting of wedges, decorative seams, narrow brim and eyelets; In the first case there are 5

(Continued)

wedges, in the second version 6 wedges; Further, on the first version there are white decorative seams imitating the visor of a cap.

1 Claim, 10 Drawing Sheets
